CLAIM

The ornamental design for washcloth, as shown and described.

DESCRIPTION

FIG. 1 is a top front perspective view of a washcloth.

FIG. 2 is a top rear perspective view thereof.

FIG. 3 is a bottom perspective view thereof.

FIG. 4 is a top view thereof.

FIG. 5 is a bottom view thereof.

FIG. 6 is a front elevation view thereof.

FIG. 7 is a rear elevation view thereof.

FIG. 8 is a left side elevation view thereof; and,

FIG. 9 is a right side elevation view thereof.

The dashed lines shown in FIGS. 1-5 represent stitches
which form no part of the claim.**1 Claim, 6 Drawing Sheets**(56)
